Inventor:

Matthew E. Campfield,

By Geo. W. Tibbitts Atty.

UNITED STATES PATENT OFFICE.

MATTHEW E. CAMPFIELD, OF CLEVELAND, OHIO.

WRENCH.

SPECIFICATION forming part of Letters Patent No. 257,468, dated May 9, 1882.

Application filed March 29, 1882. (No model.)

To all whom it may concern:

Be it known that I, MATTHEW E. CAMPFIELD, of Cleveland, in the county of Cuyahoga and State of Ohio, have invented certain new and useful Improvements in Wrenches, of which the following is a specification.

This invention relates to improvements in wrenches; and it consists in the peculiar construction of the ferrule in one piece, which 10 unites the shank of the wrench with the handle, and which also forms the socket for the head of the adjusting-screw that operates the movable jaw.

In the accompanying drawings, Figure 1 is 15 a side elevation. Fig. 2 is a longitudinal section.

A is the shank of the wrench, to which is attached the fixed jaw B, and upon which the movable jaw C slides.

20 D is a ferrule having a socket, d, to receive the end of the shank A, in which it is firmly attached by a rivet through them, or by having the end of the shank inserted through the partition-wall in the ferrule and headed down.

25 The said ferrule is also provided with a socket, d', into which a wooden handle, E, is secured by a rivet. The ferrule D is also provided with a slotted projection, F, on the upper side, having one slot, f, for the head g of the screw G,

30 and another, f', for the screw itself to revolve in, which operates the movable jaw C. The front side of said slot forms the bearing in

which the screw G revolves. The movable jaw has a screw-threaded socket, e, in which the screw G works to move it back and forth. 35 The head g is secured to the screw by a rivet, or it may be secured by forcing it onto the screw tightly. In constructing these screws I cut a long screw-rod and then cut it up into pieces of sufficient length for use.

40 The advantage of this ferrule is its firmness and solidity in attaching the shank to the wooden handle. In the old method of making a long-pointed shank and inserting it into the wood, it is liable to become loose or the handles are liable to split. This defect is entirely overcome by my improved ferrule.

45 Having described my invention, I claim—

1. In a wrench of the kind described, the head g, secured to the end of the screw G, in 50 combination with the projection F, having the two slots f and f', as and for the purpose specified.

2. The improved ferrule D, having the sockets d and d', and the projection F, and having 55 the slots f and f' for the head g of the adjusting-screw G to revolve in, in combination with the shank A, handle E, and screw G of a wrench, substantially as described.

MATTHEW E. CAMPFIELD.
